RECEPTACLE

William A. Dion, Plainville, Mass., assignor to
 Evans Case Company, North Attleboro, Mass.,
 a corporation of Massachusetts

Application October 31, 1936, Serial No. 108,657

14 Claims. (Cl. 220—55)

The invention is particularly applicable to cigarette cases, compacts and other devices for personal use although it is not confined to such purposes.

5 In general the structure comprises a receptacle having a top, bottom, ends and sides. The top may have a depending front side and the bottom may have an upstanding front side. These two front side members together may form the front 10 side of the receptacle. They may be locked in closed position by a member which is in one front side and held in position by the end members and provided with means engaging the other front side. The latching member preferably will extend both above and below the line of engagement between the front side members. This arrangement may form an effective seal for the joint between the parts of the front side and may tend to reinforce the front side members. Means 20 carried by the latching member preferably will project forward through apertures in one or the other or both of the front members but preferably the aperture or apertures will be backed and closed or reinforced by underlying portions of 25 the latching member. The latching member preferably will be made of resilient material and preferably will be so constructed, formed and arranged that its resiliency normally holds the catch engaged to hold the top member closed.

30 Preferably the latching member will be deformed as it is installed in the receptacle so that in its final position it tends to press vigorously against the front members.

In the accompanying drawing Figure 1 is a 35 perspective view of one form of receptacle made in accordance with the present invention, a portion of one end member being shown slightly withdrawn to disclose the underlying structure, the receptacle being shown open. Fig. 2 is a 40 transverse vertical section on the line 2—2 of Fig. 1, the receptacle being shown closed. Fig. 3 is a transverse vertical section on the line 3—3 of Fig. 1 the receptacle being shown closed. Fig. 4 is a fragmentary view of one end of the receptacle and Fig. 5 is a perspective view of the latching member before installation in the receptacle.

The receptacle may consist of a top member 10 provided with a depending rear side member 11 and also with a depending front side member 12. There may be a bottom member 13 provided with an upstanding rear side member 14 and an upstanding front side member 15. The end members illustrated consist of members having inwardly pressed portions 16 and overhanging marginal edges 17 associated with outwardly

extending flanges 18. The bottom member 13 and its rear and front side members 14 and 15 may rest against the edges of the member 16 and abut against the member 17 of both ends and may be fastened thereto by soldering, welding, or in any other suitable manner. The rear and forward side members 14 and 15 preferably extend upward approximately half the height of the receptacle. The rear side member 14 is connected to the rear side member 11 by a hinge 19 which may be spring controlled in any usual manner and is illustrated as extending the entire width of the receptacle. The arrangement is preferably such that when in closed position the member 14 lies in substantially the same plane with the member 11 and the combined heights of the members 11 and 14 is substantially the height of the receptacle, so that in closed position the top 10 will rest upon the top edges of the portions 16 of the end members of the receptacle. In this position the lower edge of the front side member 12 will preferably rest upon the upper edge of the front side member 15. The side members 12 and 15 rest against the front ends of the inset portions 16 of the end members while the members 11 and 14 rest against the rear ends of the portions 16 of the end members.

The latching member 20, made preferably of resilient or spring metal, may be slightly bowed as illustrated in Fig. 5. The member 20 is the 30 length of the width of the receptacle and at its ends is provided with lugs 21 and 22 to engage the end members of the receptacle. At about its middle, or at the crest of the bow, is provided a 35 projecting thumb piece 23. Adjacent this is a catching or latching aperture 24. In the front side member 15 is provided an aperture 25 to receive the thumb piece 23. When the members of the receptacle are fastened together the spring catch member 20 may be installed in place. This 40 is done by inserting the lug 22 into an aperture provided therefore at the front of the portion 16 of one of the end members. A portion of the face of the member 20 thus lies against the inner face of the member 15 and the member 20 is 45 flexed to bring the thumb piece 23 into and projecting through the aperture 25. The portion 16 of the other end member is provided with an aperture 26 to receive the lug 21 on the opposite end of the member 20 and in order to allow the 50 lug 21 to be forced into its seat a small portion of the end member 16 adjacent the aperture 26 is slotted at 27 forming a tongue 28. It is obvious that as the member 20 is brought into contact with the front member 15 and the lug 21 55

presses against it the tongue 28 may give and be slightly displaced so as to allow the lug 21 to pass beyond the end of the tongue 28 and into its seat in the aperture 26. The tongue 28 will then 5 usually return to its normal position in the plane of the portion 16 of the end member and rest against the lug 21 to hold it and the member 20 in position. If this does not occur the tongue 28 may be forced back into the plane of the portion 16 to hold the lug 21. In this position the member 20 will be held snugly against the member 15 throughout its entire length and in such position it will be in condition so that if it is displaced from close contact with the member 15 it 10 will tend to return to contact therewith.

The member 20 extends somewhat above the upper edge of the member 15 as clearly indicated in Figs. 1 and 3. Adjacent the aperture and surrounding it the member 20 may be provided with 20 an upwardly extending portion 28 which may extend upwardly so as to be nearly in contact with the top 10 when the receptacle is closed. The thumb piece 23 in the aperture 25 may extend somewhat above the top of the member 15 and 25 in order to accommodate it the depending member 12 may be provided with a corresponding aperture 30 so that when the receptacle is closed the lower edge of the member 12 may engage the upper edge of the member 15 without interference by the thumb piece 23. At the upper 30 edge of the aperture 30 the member 12 may carry an inwardly extending projection 31 which when the receptacle is closed may be engaged by the aperture 24 in the member 20 thus holding the 35 receptacle closed. In the closed position of the receptacle pressure on the thumb piece 23 may force the aperture 24 off the projection 31 and allow the top member 10 to rise. The hinge 19 may be a spring hinge to lift the top member 40 10 or the top member 10 may be lifted by hand or in any other suitable way.

The projecting portion 29 above the latching aperture 24 may be provided with an inclined, curved or bevelled edge so that as the top member 45 10 is closed the catch 31 may ride thereupon and force the member 20 backward so as to allow the projection 31 to enter the aperture 24 and be locked therein. A similar effect may be 50 procured by curving, inclining or bevelling the inner side of the projection 31 or both the cooperating members may be so treated.

To conceal the lugs 21 and 22 and the aperture 26 and tongue 28 at the end pieces any suitable means may be provided if desired. Flanges 55 18 are illustrated on the end members. The flanges 18 may be bent in slightly so that ornamental members 32 corresponding in shape to the opening between the flanges 18 may be attached by sliding between the flanges 18 where they may 60 be fastened in any suitable manner.

It will be noted that the latching member 20 extends from end to end of the receptacle and throughout its entire length underlies both front 65 side members 12 and 15 overlapping the joint between them and tending to hold the edges smooth and form a tight closure for the receptacle. The member 20 may make close contact throughout its entire length with the bottom 13. The lugs 70 21 and 22 may be so placed, or other means may be adopted, to hold the member 20 throughout all or part of its length from close contact with the bottom 13 so that if any foreign matter should get between the member 20 and the member 15 75 it will not lodge therein but may pass out by the

bottom thus leaving the member 20 continuously free to assume its position in close contact with the front members 15 and 12.

The invention is not confined to the specific structures illustrated but may be embodied in 5 other forms.

I claim as my invention:

1. In a receptacle, end walls, a bottom front wall, a top front wall separable from the bottom front wall, an inwardly extending projection on 10 the top front wall, a spring provided with an aperture engaging the projection when the receptacle is closed, the spring being mounted in the end walls so as normally to be close to the bottom front wall and extending above the top 15 edge of the bottom front wall, and means to manipulate the spring to release the projection.

2. In a receptacle, end walls, a bottom front wall, a top front wall separable from the bottom front wall, a projection on the top front wall, a 20 spring releasably engaging the projection when the receptacle is closed, the spring being mounted in the end walls so as normally to be close to the bottom front wall and extending above the top 25 edge of the bottom front wall throughout the length of the front wall, and means to manipulate the spring to release the projection.

3. In a receptacle, end walls, a bottom front wall, a top front wall separable from the bottom 30 front wall, a spring releasably engaging the top front wall when the receptacle is closed, the spring being mounted in the end walls so as normally to be close to the bottom front wall and extending above the top edge of the bottom front wall throughout the length of the front wall, and 35 means to manipulate the spring to release the projection.

4. In a receptacle, end walls, a separable top, a front wall carried by the top, a bottom, a front wall carried by the bottom in vertical alignment 40 with the top front wall, a spring member pressed against one front wall and extending beyond its free edge throughout the entire length of the said front wall, and means carried by the other front wall to engage the spring.

5. In a receptacle, end walls, a separable top, a front wall carried by the top, a bottom, a front wall carried by the bottom, a member resiliently pressed against one front wall and extending beyond its free edge throughout the entire length 50 of the said front wall, and means carried by the other front wall to engage the spring.

6. In a receptacle, end walls, a bottom front wall, a top front wall separable from the bottom front wall, a spring releasably engaging the top front wall when the receptacle is closed, the spring being mounted so as normally to be close to the bottom front wall and extending above the top edge of the bottom front wall throughout its length, and means to manipulate the spring 60 to release the projection.

7. In a receptacle, end walls, a separable top, a front wall carried by the top, a bottom, a front wall carried by the bottom, a spring member in contact with the bottom front wall and overlapping the joint between the top front wall and the bottom front wall throughout the entire length of the front wall, and releasable means carried by the front wall to engage the spring.

8. A receptacle comprising a leaf spring resting against the front wall, a side member having a seat for the spring, and a tongue adjacent the seat adapted to move to allow the spring to enter the seat and to return to hold the spring in its seat.

9. A receptacle comprising a front wall and side walls, a spring member having an inherent tendency to assume an arcuate shape, seats in the side walls for the ends of the spring adapted to hold the center of the spring against the front wall.

10. A receptacle comprising a front wall and side walls, a spring member having an inherent tendency to assume an arcuate shape, seats in the side walls for the ends of the spring adapted to hold the spring against the front wall throughout its length.

11. A receptacle comprising a front wall and side walls, a spring member having an inherent tendency to assume an arcuate shape, seats in the side walls for the ends of the spring and tongues adjacent the seats which may move to allow the spring ends to move to or from the seats.

12. A receptacle comprising a front wall and side walls, a spring member having an inherent tendency to assume an arcuate shape, a seat in one side wall for an end of the spring, and a movable member acting as a keeper for the spring in the seat.

13. A receptacle comprising a leaf spring resting against the front wall, a side member having a seat for the spring, and a tongue adjacent the seat which may move to allow the spring to enter the seat.

14. A receptacle comprising a leaf spring resting against the front wall, a side member having a seat for the spring, slots extending from the seat forming between them a movable member acting as a keeper for the spring in the seat.

WILLIAM A. DION.
